(57) **CLAIM**

The ornamental design for a low profile alternating current (AC) gateway device, as shown and described.

DESCRIPTION

FIG. 1 is a front perspective view of a low profile alternating current (AC) gateway device, showing our new design; FIG. 2 is a rear perspective view of the device of FIG. 1; FIG. 3 is a front view of the device of FIG. 1; FIG. 4 is a rear view of the device of FIG. 1; FIG. 5 is a right side view of the device of FIG. 1; FIG. 6 is a left side view of the device of FIG. 1; FIG. 7 is a top view of the device of FIG. 1; FIG. 8 is a bottom view of the device of FIG. 1; FIG. 9 is a front perspective view of the device of FIG. 1, showing our new design in a typical environment; and, FIG. 10 is a rear perspective view of the device of FIG. 1, showing our design in a typical environment.

The broken lines of FIGS. 2-8 and 10 show portions of the low profile alternating current (AC) gateway device that form no part of the claimed design. The additional broken lines of FIGS. 9 and 10 are directed to environment and form no part of the claimed design of the present application.
